UNITED STATES PATENT OFFICE.

LOUIS BAILLY, OF COLUMBUS, OHIO.

BANK, SAFE, AND VAULT LOCK AND THE LIKE.

1,406,813.

Specification of Letters Patent. Patented Feb. 14, 1922.

Application filed February 21, 1921. Serial No. 446,738.

To all whom it may concern:

Be it known that I, LOUIS BAILLY, a citizen of the Republic of France, residing at Columbus, in the county of Franklin and 5 State of Ohio, have invented certain new and useful Improvements in Bank, Safe, and Vault Locks and the like, of which the following is a specification.

My present invention relates generally to 10 locks and more particularly to bank, safe and vault locks and the like, my primary object being the provision of a combination lock in which the various parts operate and are immersed in fluid so as to render it impossible to hear or detect from the outside their 15 movement or relative positions and in this way defeat any attempt of unwarranted opening or release of the lock.

A further object is the provision of a 20 lock having an extremely wide range of change of combination, as well as one in which the change can be readily and easily effected.

A still further object is the provision of 25 a fluid lock in which release is effected by the pumping of a fluid whose circulation is prevented with the locked parts in set or locked position.

With these general objects in mind other 30 objects residing more particularly in the features of construction, arrangement and operation, as well as the resulting advantages of my invention will be better understood from the following description, wherein reference is made to the accompanying drawings, forming a part of this specification, and wherein,

Figure 1 is a front elevation of a safe to 35 which my invention is applied,

Figure 2 is a front elevation of my improved lock,

Figure 3 is a top plan view of the permutation wheels,

Figure 4 is a central vertical section 40 through the lock showing the parts in position for release,

Figure 5 is a partial vertical section, certain parts being omitted, with the controlling parts in locked or set position,

Figure 6 is a horizontal section taken on line 6-6 of Figure 5,

Figure 7 is a partial side view of one of the tumbler disks,

Figure 8 is a partial vertical section 45 through one of the disks shown in Figure 7,

Figure 9 is a partial vertical section through one of the bearing rings,

Figure 10 is a partial side view of the tumbler ring seat,

Figure 11 is a partial section therethrough, 60

Figure 12 is a detail cross section taken through the sleeve of the cylinder substantially on line 12-12 of Figure 4,

Figures 13 and 14 are respectively a front and a side view of the tumbler ring actuating collar, 65

Figure 15 is a side view of the plunger, and

Figures 16 and 17 are respectively a side view partly broken away and a front view 70 of one of the combination rings to be hereinafter described.

Referring now to these figures and particularly to Figure 1 I have shown a safe generally indicated at 20, having a door 21 which is opened and closed by a handle 22 mounted upon the outer end of a rotatable bolt throwing shaft 23, the latter being indicated in dotted lines in Figure 2 and being normally locked against rotation by a lever 24, one end of which has an angular extension 25 shiftable upwardly into and downwardly out of a notch or recess 26 of shaft 23. Lever 24 is fulcrumed intermediate its ends at 27 upon a bracket 28 and its free end 29 is disposed above the upper end of an actuating and controlling pin 30, the latter of which in its normal lowermost position permits lever 24 to swing by gravity until its angular locking extension 25 projects into 80 the notch or recess of the shaft 23, and upward movement of which pin 30 rocks lever 24 on its fulcrum 27 and causes lowering movement of its angular end 25 out of engagement with the bolt throwing shaft 23 85 so that the latter is then free for manual rotation by the handle 22 in order that the safe door 21 may be opened.

As shown in Figure 2 the pin 30 is mounted axially through the upper closing 100 plug 31 of a vertically disposed piston cylinder 32 which extends upwardly from and forms a part of the cylindrical lock housing 33 whose front wall 34 abuts the inner or rear surface of the door 21 and has a reduced 105 cylindrical extension 35 projecting forwardly through a bore formed in the door 21 for the reception of this extension.

The lower end of pin 30 in its cylinder 32 carries a piston 36, the lower end of cyl- 110

- linder 32 having an opening 37 through which fluid from the lock housing 33 may be forced upwardly against piston 36 to shift the pin 30 vertically in its operative movement against the tension of a spring 38 coiled around the pin 30 and compressed between the upper surface of the piston 36 and the lower surface of the cylinder closing plug 31.
- 10 The inner or rear side of the housing 33 is closed by a removable cover plate 39 disposed rearwardly of and in spaced relation to an enlarged circular tumbler ring 40, the latter of which has a forwardly turned flange 41 movably interfitting the rear portion of the housing 33 and provided at one point with an opening 42 adapted to be moved into registry with the opening 37 of the base of the piston cylinder 32. With the 20 space 43 between the detachable cover plate 39 and the tumbler ring 40, the piston cylinder 32 has communication through an opening 44 which is formed intermediate the ends of the cylinder 32 at such a point that fluid can escape into the space 43 from the piston cylinder when the piston 36 has been shifted upwardly a sufficient distance to bring about proper elevation of the actuating pin 30 of the controlling lever 24.
- 30 The space 43 also communicates with the rear end of a rotatable cylinder 45 through a spring controlled valve 46 which opens forwardly into the rear end of cylinder 45 and is mounted within a plug 47 closing the 35 rear end of the cylinder against the flow of fluid from the cylinder to the space 43.
- Cylinder 45 is mounted axially of the lock housing 33 and upon its rear or inner end the combination plate 40 is adjustably mounted 40 at its center and normally locked in connection with the cylinder by a lock nut 48. Cylinder 45 has a single opening 49 in its wall adjacent to the front wall 34 of the lock housing and is rotatably mounted 45 through a sleeve 50, the latter of which is in turn rotatably mounted through the reduced forward extension 35 of the lock housing and has an annular series of apertures 51 opposite the single opening 49 of cylinder 45 as seen in Figure 4 and also seen by reference to Figure 12, openings 51 being in the nature of circumferential slots as shown so that there will always be communication between the interior of 50 cylinder 45 forwardly of the pump plunger and the space within the lock housing 33 around the sleeve 50 and forwardly of the forward and rear combination rings 52 and 53.
- 55 The forward ends of cylinder 45 and sleeve 50 project forwardly beyond the outer surface of the door 21 and have permutation disks 54 and 55, each of which is provided with peripheral numbers, the numbers of 60 the disk 55 cooperating with a pointer 56 on the door 21 and the numbers of the disk 54 cooperating with a pointer 57 on disk 55. Disk 54 has an additional series of peripheral numbers with which a pointer 58 on the outer handle 59 of the plunger stem 70 60 cooperates. This stem extends axially through the forward portion of cylinder 45 and carries a plunger 61 upon its inner end operating in the cylinder and having a movable spring controlled skirt portion 62 75 adapting the same to the ready movement of fluid forwardly past the plunger in the rearward movement of the plunger, which fluid is upon the forward movement of the plunger forced outwardly through the openings 49 and 51 when the plunger is held in properly rotated position within the cylinder 45 to register the slot 63 of its skirt portion 62 with the cylinder opening 49.
- 80 Mounted around the sleeve 50 within the lock housing is a collar 64 having a rib 65 outstanding between the inner portions of the tumbler rings 52 and 53, the latter of which are mounted to loosely rotate upon the collar 64 at opposite sides of rib 65. Each of the tumbler rings 52 and 53 has against its inner surface an actuating ring 66, these two actuating rings having inturned opposing peripheral flanges 67 around the periphery of the rib 65 and spaced therefrom, 95 each flange 67 having an internal shoulder 68, the shoulder of one flange being turned in one direction and the shoulder of the other flange being turned in the opposite direction for cooperation with the laterally offset opposite ends 69 of a spring 70 secured at its center as at 71 upon the periphery of the rib 65 so that its free ends project into engagement with the inner surfaces of the flanges 67, thus adapting rotation of the sleeve in one direction to be communicated to the tumbler ring 52 and rotation of the sleeve in the opposite direction to be communicated to the tumbler ring 53.
- 100 Each of the inner actuating rings 66 of the tumbler rings 52 and 53 is furthermore provided with slotted openings 72 as particularly shown in Figure 17, bolts 73 being utilized to secure the rings by passage through the slots 72 so that upon loosening these bolts the tumbler rings and their actuating rings may be adjustably shifted through a range of approximately 180° in changing the combination of the lock.
- 110 At their outer portions the tumbler rings 52 and 53 have inclined peripheral flanges 74 and 75, movable upon and against the inclined opposite side surfaces of a tumbler ring seat 76 of annular form which is mounted within the lock housing 33 and is adjustably secured to the latter by a set screw 77. This tumbler ring seat 76 in cooperation with the tumbler rings 52 and 53 normally forms a dividing wall between the forward and rear portions of the lock housing 33 to prevent the 115 120 125 130

flow of fluid from the space of the lock housing forwardly of such wall to the space of the lock housing rearwardly of such wall, thus normally cutting off communication between 5 the openings 49 and 51 of the cylinder 45 and sleeve 50, and the openings 42 and 37 of the tumbler plate 40 and the piston cylinder 32. The tumbler ring seat 76 has however a transverse opening 78 at one point with 10 which openings 79 and 80 of the tumbler ring flanges 74 and 75 may be alined so that when alined, fluid may be pumped upon actuating plunger 61 from the exterior of the lock, through openings 49 and 51 of the plunger cylinder 45 and sleeve 50 and thence through the alined openings 78, 79 and 80 to the rear portion of the lock housing and from there through the openings 42 and 37 when the latter are alined.

20 The tumbler rings 52 and 53 are under tension of springs 81 and 82 by which they are pressed toward one another into even uniform engagement with the opposite sides of their seat 76, and for the sake of uniformity in action of the springs 81 and 82, each tumbler ring has an annular outstanding flange 83 at the inner portion of its inclined peripheral flange. Each flange 83 movably supports a bearing plate 84 against which 25 the respective spring 81, 82 engages, the bearing plate 84 in turn being apertured as at 85 so as not to check free movement of the fluid. Bearing plate 84 of the tumbler ring 52 movably engages the inner surface of 30 the front plate 34 of the lock housing 33 while the bearing plate 84 of the tumbler ring 53 movably engages the forward surface of the tumbler plate 40.

40 In operation the interior of the lock housing is filled with a fluid, for instance oil, which is unaffected by climatic changes, and the space 43 between the tumbler plate 40 and the removable cover plate 39 is also filled with similar fluid. The disk 55 of 45 the sleeve 50 is then turned first in one direction and then the other to respectively rotate the tumbler rings 52 and 53 to the position shown in Figure 4 with their openings 79 and 80 in registry with one another and the opening 78 of the tumbler ring seat 76. The permutation disk 54 of the cylinder 45 is then turned to the proper position for registering the opening 42 of the tumbler plate 40 with the opening 37 of the base 50 of the piston cylinder 32, the opening 49 of the cylinder registering in any position of rotation with one of the circumferentially slotted openings 51 of the sleeve 50. It is then only necessary to 55 rotate the plunger stem 60 until the slot 63 of its skirt portion 62 registers with the cylinder opening 49 in order to properly position all of the parts for the free movement of fluid into the lower end 60 of the piston cylinder 32 upon the actuation

of the pump plunger by manipulating the plunger stem 60 inwardly and outwardly. During the course of this movement fluid is taken in to the inner or rear end of cylinder 45 through the valve 46, from the space 70 43 and moves forwardly past the plunger 61 and from the forward portion of the cylinder 45 passes outwardly through the slot 63 and openings 49 and 51, then through the openings 85 of the bearing plate 84 and 75 then to the rear of the lock housing 33 through the alined openings 78, 79 and 80 of the tumbler rings and their seat. The fluid is then free to pass into the lower portion of the piston cylinder 32 through the 80 openings 42 and 37 so as to raise the piston 36 and thus shift the pin 30 vertically in order to move lever 24 out of engagement with the bolt throwing shaft 23. When pin 30 has elevated sufficiently for this purpose 85 the piston 36 will be shifted to a point above the opening 44 of the piston cylinder 32 so that in any further actuation of the plunger 61 the fluid will move through this opening 44 and back into the space 43 between the 90 tumbler plate 40 and the detachable inner or rear cover plate 39. It is quite obvious that when operative movement of the plunger is stopped, the fluid within the lock housing and the lower portion of the piston 95 cylinder 32 will hold the piston 36 in elevated position. This position of the parts will continue until after the door 21 has been again closed and it is desired to lock the same. The sleeve 50 and cylinder 45 100 may be rotated to shift the tumbler rings and the tumbler plate out of the alined position shown in Figure 4 to a position such for instance as shown in Figure 5, but it is quite obvious that the piston 36 will still be 105 held in the upper position. Piston cylinder 32 is then provided with a second opening 86 adjacent to its base and communicating with the space 43 under control of a valve 87 normally held in seated position by a spring 88 110 whose strength is such as to resist tendency of the valve 87 to open under pressure of the fluid alone. This valve 87 is mounted upon a stem 89 projecting rearwardly through the cover plate 39 and provided with a down-turned end 90 engaged by one forked end 91 of a lever 92 fulcrumed at 93 upon a rearwardly projecting bracket 94 of the cover plate 39, the opposite forked end 95 of which lever 92 is engaged by the angular inner end 115 of a stem 96 which projects forwardly through the door 21 and has a handle 97 at its forward end. Thus when the handle 97 is pulled forwardly by the operator the valve 87 will be shifted rearwardly against the 120 tension of spring 88 and opening 86 will be uncovered for the flow of fluid from beneath the piston 36 to the space 43 so as to allow piston 36 and the lever actuating pin 30 to descend and in turn permit shaft locking 125 130

lever 24 to rock to the operative position shown in dotted lines in Figure 2.

In changing the combination, by rotating either or both of the tumbler rings 52 and 53 with respect to their actuating rings 66, or rotating the tumbler plate 40 with respect to the cylinder 45, it is obvious that the detachable rear cover plate 39 must first be removed. This will permit of outflow of the fluid of course, and to facilitate and control such outflow, the lower inner portion of the lock housing 33 may have a curved trough 98 as particularly shown in Figure 4 terminating at its lower portion in a discharge 10 spout 99 so that by placing a suitable receptacle beneath this spout the fluid may be caught and after change of the combination and re-connection of the cover plate 39 this fluid may be re-introduced within the lock 15 housing through a filling aperture at the upper portion of the cover plate 39 normally closed by a plug 100.

It is obvious that by virtue of the relatively large diameter of the tumbler rings 25 and the tumbler plate 40 as well as the fact that the combination may be changed by adjustment of either or all of these parts, that a very wide range of change of combination is permitted, and it is quite obvious 30 that by virtue of the fact that the several parts are immersed and move in a fluid, their relative shifting movements will be noiseless and attempts to solve the combination of the lock by feel will be defeated.

35 My improved lock not only requires that the combination be actually known before release can be effected, but is of strong construction and will be lasting and durable in use.

40 I claim:

1. A fluid lock including a housing forming a fluid casing, a fluid pumping means therein, a piston actuated lock controlling member operated and controlled by the fluid 45 from said pumping means, and a plurality of manually actuated members shiftable to establish and cut off the passage of fluid from the pumping means to the said piston actuated member.

50 2. A fluid lock including a housing forming a fluid casing, a fluid pumping means therein, a piston actuated lock controlling member operated and controlled by the fluid from said pumping means, and manually 55 actuated means controlling the passage of fluid from the pumping means to the said piston actuated member including a series of independently movable tumblers having apertures shiftable into and out of alignment with the fluid passage.

60 3. A fluid lock comprising a housing forming a fluid holding chamber, means therein forming a fluid circulating passage, a lock controlling member actuated by the movement of fluid through said fluid passage, and

a pump for moving the fluid, said passage forming means including a plurality of members independently shiftable to open and close the passage.

4. A fluid lock comprising a housing forming a fluid holding chamber, means therein forming a fluid circulating passage, a lock controlling member actuated by the movement of fluid through said fluid passage, a pump for moving the fluid, said passage 75 forming means including a plurality of members independently shiftable to open and close the passage, and means with which said last named members are adjustably connected, for shifting the same from the exterior of the housing.

5. A fluid lock comprising a housing, a piston cylinder, a piston actuated lock control member in said piston cylinder, a member controlling communication between the piston cylinder and the housing, a pump cylinder in the housing, a manually actuated plunger in said latter cylinder, and manually actuated fluid control members in the housing between the pump cylinder and 90 the first named controlling member.

6. A fluid lock comprising a housing forming a fluid chamber, fluid actuated bolt controlling means, manually actuated fluid pumping means in the housing, and means 95 forming a fluid passage between the bolt controlling means and the pumping means, including manually and independently shiftable fluid control elements in the housing movable to open and close said passage.

7. A fluid lock comprising a housing forming a fluid chamber, fluid actuated bolt controlling means, manually actuated fluid pumping means in the housing, and manually shiftable fluid control means in the housing, between the pumping means and the fluid actuated means, said last-named means consisting of apertured tumblers normally immersed and shiftable in the fluid holding chamber.

8. A fluid lock comprising a housing forming a fluid chamber, fluid actuated bolt controlling means, manually actuated fluid pumping means in the housing, and manually shiftable fluid control means in the housing between the pumping means and the fluid actuated means, said last-named means consisting of apertured tumblers in the fluid chamber and having externally projecting shifting means with which the tumblers are 110 adjustably associated.

9. A fluid lock comprising a housing forming a fluid chamber, fluid actuated bolt controlling means, manually actuated fluid pumping means in the housing, and manually shiftable fluid control means in the housing between the pumping means and the fluid actuated means, said fluid actuated means being in the nature of a piston having an externally projecting pin as described.

10. A fluid lock comprising a housing forming a fluid chamber therein, a pump cylinder axially of the housing having an externally projecting portion, a plunger in 5 said cylinder having an externally projecting stem, a sleeve around the cylinder having openings through which the cylinder discharges into the forward portion of the housing and also having an externally projecting portion, a pair of oppositely acting and rotatable tumbler rings around the sleeve, having a seat in the housing and normally dividing the same into non-communicating forward and rear portions, said 10 rings and their said seat having apertures movable into registry, means carried by the sleeve for rotating said rings in relatively opposite directions, a piston actuated bolt controlling member, a cylinder in which said 15 member operates, opening into the rear portion of the housing, and a member controlled by rotation of the pump cylinder for controlling communication between the housing and said piston cylinder.
- 20 11. A fluid lock comprising a housing forming a fluid chamber therein, a pump cylinder axially of the housing having an externally projecting portion by which it may be rotated, a plunger in said cylinder having an externally projecting stem, a sleeve around the cylinder having openings through which the cylinder discharges fluid into the forward portion of the housing and also having an externally projecting portion 25 by which it may be rotated, tumbler rings around the sleeve, a seat for the tumbler rings cooperating with the latter to divide the fluid chamber into normally separate forward and rear portions, said rings and 30 their said seat having apertures movable into registry upon registration of the rings, a collar around and secured to the sleeve between the tumbler rings, actuating rings adjustably secured to the tumbler rings adjacent to the said collar, cooperating means on the collar and the said actuating rings whereby to rotate the tumbler rings in relatively opposite directions upon corresponding rotation of the sleeve, a piston actuated 35 bolt controlling member, a cylinder in which said member operates adjacent to the rear portion of the housing, and means adjustable with the pump cylinder for controlling communication between the rear portion of the 40 fluid chamber and the said piston cylinder.
- 45 12. A fluid lock comprising a housing forming a fluid chamber therein, a pump cylinder axially of the housing having an externally projecting portion by which it may be rotated, a plunger in said cylinder having an externally projecting stem, a sleeve around the cylinder having openings through which the cylinder discharges into the forward portion of the housing and also 50 having an externally projecting portion, a pair of tumbler rings having a seat in the housing and normally dividing the fluid chamber into non-communicating forward and rear portions, said rings and their seat having apertures movable into and out of 55 registry, means carried by the sleeve for rotating the rings and with respect to which the said rings are secured in rotatable adjustable relation, a piston cylinder at the upper rear portion of the housing having an 60 opening in its face communicating with the fluid chamber, a piston in said cylinder, a bolt controlling member carried by the piston, and a circular tumbler plate in the rear portion of the housing and mounted on and 65 rotating with the pump cylinder, having a peripheral flange movable below the lower opening of the piston cylinder and provided with an aperture movable therewith into and out of registry with the said piston 70 cylinder opening.
- 75 13. A fluid lock comprising a housing forming a fluid chamber therein, a pump cylinder axially of the housing having an externally projecting portion by 80 which it may be rotated and having a discharge opening in communication with the forward portion of the fluid chamber, a plunger shiftable and rotatable in said cylinder, having an externally projecting stem by which it may be shifted and rotated and having a skirt provided with a lengthwise slot movable upon rotation thereof into and 85 out of registry with the discharge opening of the cylinder, a sleeve around the cylinder having an externally projecting portion by which it may be rotated, a pair of apertured tumbler rings controlled by the sleeve and seated in the fluid chamber to normally 90 control communication between the front and rear portions of the chamber, a piston actuated bolt controlling member, a cylinder in which said member operates having communication with the rear portion of the fluid chamber, and a member controlled by rotation of the pump cylinder for controlling communication between the piston cylinder and the fluid chamber.
- 95 14. A fluid lock comprising a housing forming a fluid chamber therein, a pump cylinder axially of the housing having an externally projecting portion by which it may be rotated, a plunger in said cylinder, a sleeve around the cylinder having openings through which the cylinder discharges 100 into the forward portion of the housing in advance of the plunger, and also having an externally projecting portion by which it may be rotated, a pair of tumbler rings dividing the fluid chamber and controlling 105 communication between the forward and rear portions thereof, means carried by the sleeve for adjusting the said rings, a piston actuated bolt controlling member, a cylinder in which said member operates having 110
- 115 120 125 130

communication with the rear portion of the fluid chamber, a tumbler plate closing the rear portion of the fluid chamber, said tumbler plate being mounted on and movable by the pump cylinder and having means to control communication between the fluid chamber and the piston cylinder, a detachable cover plate at the rear of the housing spaced from the said tumbler plate to form a compartment therebetween, said piston cylinder having an opening intermediate its

ends communicating with the said compartment, an intake valve controlling communication between said compartment and the rear end of the pump cylinder, and manually actuated means normally controlling communication between the said compartment and the lower end of the piston cylinder as described. 15

In testimony whereof I have affixed my 20
signature.

LOUIS BAILLY
